UNITED STATES PATENT OFFICE.

HERBERT EDWARD SHREEVE, OF MILBURN, NEW JERSEY, ASSIGNOR TO WESTERN ELECTRIC COMPANY, OF NEW YORK, N. Y., A CORPORATION OF ILLINOIS.

MICROPHONE.

1,134,236.

Specification of Letters Patent. Patented Apr. 6, 1915.

Original application filed May 25, 1911, Serial No. 629,261. Divided and this application filed December 26, 1913. Serial No. 808,732.

To all whom it may concern:

Be it known that I, HERBERT EDWARD SHREEVE, a subject of the King of Great Britain, residing at Milburn, in the county 5 of Essex and State of New Jersey, have invented a certain new and useful Improvement in Microphones, of which the following is a full, clear, concise, and exact description.

10 This invention relates to telephonic devices and more particularly to a microphonic device in which the resistance varying medium is comminuted material retained between two relatively movable contact elements constituting walls of a containing chamber, and is a division of my copending application, Serial Number 629,261, filed May 25, 1911.

15 The object of this invention is to provide means in connection with such a microphonic device for automatically maintaining the comminuted material in a condition for obtaining the most beneficial results.

20 In accordance with this invention the chamber containing the comminuted material has one wall which operates by expanding and contracting toward and away from the comminuted material under the direct influence of the heat generated in the chamber to prevent packing of the comminuted material. This feature is preferably obtained by use of a thermostatic diaphragm in the chamber containing the comminuted material. Such a diaphragm may be made 25 of plates of two metals of dissimilar coefficients of expansion and it has been found that gold and iron are suitable metals for this purpose.

25 The drawing illustrating this invention is 40 a cross-sectional view on an enlarged scale of a microphonic element.

As shown in the drawing, 5 designates a metal cup in which is secured a stationary electrode, preferably of carbon, which is secured to a metal button 7 having a screw-threaded stud 8 extending through the wall of the container 5 to receive a clamping nut 9. The metal disk 7 is insulated from the wall of the chamber 5 by means of an insulating disk 10 and the clamping nut 9 is separated from the outer wall of the chamber by an insulating washer 11. Secured to the front wall of the chamber 5 by means of

a screw-threaded clamping ring 12 engaging screw threads 13 upon the wall of the chamber 5, is a diaphragm formed of two thin plates of metal 15 and 16. The inner one 15 is preferably of gold and the outer one 16 is of iron. These plates are clamped together at their outer edges between the outer margins of the chamber 5 and a flange 17 formed upon the clamping ring 12. Centrally mounted upon the diaphragm is a metal rod 20 which may serve as one terminal of an electric circuit when the device is used in a transmitter, or when this device is used in a repeater this member 20 may be formed of iron and constitute a pole piece to coöperate with the receiving element of the repeater. The microphonic element thus constructed is 25 partly filled, as shown, with comminuted material, preferably granular carbon, the circuit through it being directly from one electrode to the other. Electrical connections may be made to member 20 and an extension 22 of the screw-threaded stud 8.

30 The action of the diaphragm formed of the two metals of dissimilar coefficients of expansion is such that any tendency of the comminuted material to pack will cause said 35 diaphragm to move away from the opposing electrode, thereby relieving the pressure and maintaining the transmitter button in a sensitive state or condition. Gold has a higher coefficient of expansion than iron and gives 40 a good contact surface for the carbon granules while iron serves as an element of the thermostat. The gold plate lying next to the comminuted material and expanding more rapidly than the other, the diaphragm 45 moves inwardly upon any increase in temperature in the granular chamber and conversely moves outwardly upon a decrease in the temperature. It will be seen therefore that during the flow of current through the 50 resistance varying medium there is a gradual increase in temperature which will at first cause a gradual inward moving of the diaphragm. This action, however, is followed by a tendency of the granules to pack, thus 55 lowering the resistance and consequently decreasing the heating effect of the granular material. This decrease in temperature results in a cooling of the diaphragm and a consequent movement of the diaphragm outwardly, whereupon the granules are relieved 60

of pressure and resistance and temperature are again increased, thus causing the diaphragm to again move inwardly. It has been found in practice that a diaphragm 5 constructed in this manner has a periodic movement forward and backward, the period being of about thirty to forty seconds duration. This movement although extremely slight and impossible of direct observation 10 is sufficient to keep the carbon granules in a free and sensitive state.

What I claim is:

1. In a microphonic device, a container 15 for comminuted material having as one wall a thermostatic diaphragm arranged to bend inwardly and outwardly with varying degrees of heat generated by the flow of current through said device.
2. In a microphonic device, comminuted 20 material and a container therefor having as one wall a movable diaphragm composed of two plates of different coefficients of expansion and responsive to heat generated by the flow of current through said device to 25 vary the pressure upon the comminuted material.
3. In a microphonic device, a container for a granular resistance varying material having as one wall a thermostatic dia-

phragm adapted to bend outwardly with decreasing temperature.

4. In a microphonic device, a container 30 for granular resistance varying material having as one wall a thermostatic diaphragm adapted to bend inwardly with increasing 35 temperature and outwardly with decreasing temperature.

5. In a microphonic device, a container for 40 comminuted material having as one wall a thermostatic diaphragm adapted in response to heat conducted from the granules to automatically relieve the pressure of the granules upon a tendency thereof to pack.

6. In a microphonic device, comminuted 45 material and a container therefor having as one wall a movable diaphragm composed of plates of gold and iron and responsive to heat generated by the flow of current through said device to vary the pressure upon the comminuted material. 50

In witness whereof, I hereunto subscribe my name this 20th day of December, A. D., 1913.

HERBERT EDWARD SHREEVE.
